DESIGN FOR A METAL CEILING

Frank M. Vogan, Canton, Ohio, assignor to The Canton Metal Decorating Company, Canton,
Ohio, a corporation of Ohio

Application September 12, 1935, Serial No. 58,535

Term of patent 3½ years

To all whom it may concern:

Be it known that I, Frank M. Vogan, a citizen of the United States, residing at Canton, in the county of Stark and State of Ohio, have invented a new, original, and ornamental Design for Metal Ceilings, of which the following is a specification, reference being had to the accompanying drawing, forming part thereof.

The figure is a plan view of a panel of metal ceiling, showing my new design.

I claim:

The ornamental design for a metal ceiling, as shown.

FRANK M. VOGAN.
